LUDWIG GLATZ, OF CINCINNATI, OHIO.

EXTENSION-TABLE.

1,180,841.

Specification of Letters Patent. Patented Apr. 25, 1916.

Application filed September 5, 1914. Serial No. 860,332.

To all whom it may concern:

Be it known that I, LUDWIG GLATZ, a subject of the Emperor of Austria-Hungary, and a resident of Cincinnati, in the county of Hamilton and State of Ohio, have invented a certain new and useful Improvement in Extension-Tables, of which the following is a specification.

This invention relates to extension-tables of the class that is generally or commonly known as the pedestal type in which the normal table or table-proper can be extended from two opposing parallel sides of its main or normal body portion that contains the stationary supporting-pedestal structure, and the object of the invention is to provide means whereby the extensible portions can be drawn lengthwise from two opposite parallel sides of the main-table on an elevating or gradually higher-level plane so that the extra boards or leaves used can be carried in a piled-up state by the outermost pairs of slides at each of said sides of the main-table and, when the inner pairs of the said two pairs of slides have been extended and elevated to the desired level, the said piled-up extra leaves can be unfolded on their hinges, which is the preferred manner of arranging them, and turned inwardly toward the main-table and used as fillers in the space or gap that lies between the outermost extended leaf or board of each set of piled-up leaves and the next adjacent parallel edge of the main-table top.

35 A further object is to provide a suitable opening or space beneath the main-table top for pocketing the piled-up leaves above the slides when the latter are in pushed-up or closed position above the supporting-pedestal, whereby the extra leaves are kept out of sight and are ready for immediate extended use, and need occupy no other place that is inconvenient and remote from the main-table when they are not in use.

45 A compact and sightly structure is thus provided that serves as a main-table without its leaves being extended, or as a well-supported extension-table when its leaves are unfolded on the extended slides whose outermost ends are duly supported by means of foldable legs, all of which will be hereinafter fully described and particularly pointed out in the claim.

In the accompanying sheets of drawings forming a part of this specification, Figure 1 is a plan view of my improved table show-

ing the normal top or permanent center thereof that is mounted on a pedestal or standard with one of the extensible structures or ends drawn outward in position for 60 use and with the other extensible structure or end in closed position out of use; Fig. 2, a longitudinal side elevation of Fig. 1; Fig. 3, a plan view similar to Fig. 1 but showing the table with its permanent top and the extension devices of one side removed and the leaves of the extended side also removed, and, also, with the longitudinal center of the whole device broken away whereby a clear view of the pick-up and stop devices 70 for the extensible-slides is obtained; Fig. 4, a central longitudinal section of the table as it appears in Fig. 1 and taken on the dotted-line x, x , of Fig. 3, but before the piled-up leaves have been unfolded into us- 75 ing position and with the pedestal omitted; Fig. 5, an elevation of one of the extensible-slides of the table, showing half in section, however, and with the parts closed in normal position without any extension there- 80 of; Fig. 6, a fragmentary perspective view, on a somewhat larger scale than the other views just described, showing two of the extensible-slides in engaging position at the extreme outer end of their extended stroke, 85 and bringing to clear view one of the pick-up spring-latches and its adjacent stop and actuating cam-plate that is used in coupling the slides so that they recede or return together when the table is to be put in normal, 90 closed position; Fig. 7, a fragmentary perspective view of one of the grooved partitions in the main-table frame showing its inclined T-shape groove or guide-way for directing the gradual elevation of the ex- 95 tensible-slide seen in Fig. 6, and further showing the laterally-extended plate used as a switch or shifter for the said spring-latch seen in Fig. 6; Fig. 8, a detail section of the spring-latch seen in Fig. 6; Fig. 9, a 100 combination plan and projected end view of one of the laterally-extended coupling-plates used on the bottom of the adjacent extended ends of the two slides seen in Fig. 6 for the outward pull or draft of the inner 105 slide shown; Fig. 10, a view similar to Fig. 9 but showing the reverse side of the switch or shifter plate seen in Fig. 7 and being one of those used in actuating the spring-latch devices of the extensible-slides 110 and showing both of the bottom outer corners as being beveled; Fig. 11, a view simi-

lar to the last two views but showing one of the stop and shifter plates, such as that seen on the inner slide of Fig. 6 and used in controlling the backward or reverse movement of the extensible-slides in retreating from extended use; Fig. 12, a fragmentary outside elevation of the grooved partition seen in Fig. 7; Fig. 13, a bottom plan view of the two extensible-slides seen in Fig. 6, 10 showing the interlocking or coupling plates on the bottom of the two slides that are mentioned in connection with Fig. 9; Fig. 14, a detail outside elevation of the auxiliary or inner one of the slides seen in Fig. 6, 15 it being the slide that is used in both extending and elevating the leaves to the proper level for use; and Fig. 15, a transverse section, taken on a slightly larger scale, of the auxiliary-slide seen in Fig. 14 20 and, also, taken on the vertical dotted-line y, y , of that view.

In these drawings, 1 indicates the pedestal or upright, central supporting-standard having a bottom or base 2 that carries auxiliary 25 corner-posts 3, the latter, in turn, carrying the rectangular, extension-slide containing-receptacle or housing-frame whose details of structure I shall presently describe and which also carries the main-table top 4 that 30 is suitably held vertically-spaced therefrom by means of right-angled bracket-plates 5 projecting upwardly from the opposite ends of the two outer side-bars 6, 6 of the said housing-frame (as in Figs. 1, 2, 3 and 5). As 35 the extensible devices are duplicated at both the open sides or ends of the said receptacle and the latter is made with corresponding guideways and walls for the accommodation of the slides, I shall describe but one set of 40 the four extensible sets in actual detail and the manner in which all four sets of slides coact in the operation of making-up an extension-table according to my invention herein.

45 7 indicates an auxiliary slide and coupling bar arranged contiguous to the inner face of one of the outer side-bars 6 and having an inclined tongue or tenon formation 8 along one of its side faces that engages an inclined 50 groove 9 in the adjacent inner face of the said outer side-bar 6, both tongue and groove being T-shape in cross-section and said slide and coupling bar 7 also having on its opposite face a horizontal T-shape tongue-formation 10 that engages a T-shape groove 11 made in the contiguous face of a slide-bar 12 that projects inwardly toward the main-table from near one end of the outermost or extreme extension leaf or cross-board 13 that carries two subsidiary extra leaves or cross-boards 14 and 15, the latter being hinged together and carried in folded condition by said outermost board 13 when the table is closed, or when the table is being 60 either extended or closed, as the case

may be. (Fig. 4 shows the piled-up feature of the leaves 14 and 15, in both extended and closed positions.)

The inner face of the slide-bar 7 is smooth and plane and contacts with the smooth and plane outer face of an intermediate stationary partition or guide-bar 16 that parallels the said outer side-bar 6 and has a T-shape groove 17 in its opposite face or inner side, such groove 17 being inclined at the same angle as the inclined groove 9 but in the opposite direction to accommodate the auxiliary slide and coupling bar 7 that approaches within the receptacle or housing-frame from the opposite open end thereof and has a similar T-shape tongue-formation 8 thereon for engagement with its companion groove. A plane, stationary inside bar 18 is arranged parallel to the said intermediate partition-bar 16 but duly spaced 70 therefrom to accommodate the last-named coupling-bar 7 and form a suitable guideway with said partition-bar 16 therefore, the smooth and plane inner face of an inwardly-extending bar 12 that approaches 75 from the other end of the receptacle or housing-frame but projecting from an outermost extension-board 13 a greater distance from the side edge of the latter than that of the slide-bar 12 first-above-described (as 80 in Fig. 3, but wherein the slide devices to the left are omitted.)

A transverse bar 19 is provided at the center of the housing-frame (as in Figs. 2, 3 and 4), suitably elevated above the upper edges of the sets of slide-bars 7 and 12 and the guide-bars 6, 16 and 18 at both sides of the housing-frame, (as best seen in Fig. 5). When the piled-up leaves at the outer ends of the outermost extension-bars 12 are 100 housed within the main-table receptacle, (as in Figs. 2 and 4) the inner edge of the uppermost leaf of each piled-up set contacts with the side edge of the cross-bar 19 and the outer edge of the piled-up sets of leaves 105 lies flush with that of the table-top 4 (as in said Figs. 2 and 4), thus imparting a smooth and finished appearance to the table when closed and unextended. The top surface of the cross-bar 19 contacts with the 110 bottom of the table-top 4 and is flush with the top surface of the upper folded leaf 15 (Fig. 4).

In order to support the leaves and slides in their extended position (Fig. 2) I provide a pair of legs or props 20 that are connected by means of a cross-bar 21 and hinges 22 to the apron or pendent cross-bar 23 that is secured to the outer edge of the outermost board 13 of each of the extension 115 sides of the table, said hinges enabling the folding of the legs into a horizontal position beneath the boards 13 and 14 when the slide devices are being operated to and from within the housing-frame and when the 120 125 130

slide devices and extra leaves are in closed position within said housing-frame, (as in Figs. 2, 3 and 4). A suitable latch-bolt 24 is provided beneath the board 13 to hold the legs or props in folded position, (see Fig. 4). A reinforcing cross-bar 25 is provided between the legs 20 (see Fig 4).

In order to reciprocate the extension devices to and from place within the table, I provide the slide-bars 12 with pivotal-plates 26 mounted on cross-pins 27 in bearings 28 (Figs. 3, 6 and 8), on their upper edges and laterally-extending plates 29 on their bottom edges or faces, the latter-named edges being tenoned at 30 and the said plates 29 extending beyond the inner edges of the tenons but not beyond the inner plane faces of the said slide-bars 12 (as best seen in Fig. 13). The stationary parallel guide-bars 16 and 18 of the housing-frame are each provided with laterally-extending plates 31 (Figs. 3, 7 and 12) that form switches on their upper edges, such lateral extensions or switches lying in the path of the elevated or raised part 26^a of the said pivotal-plates 26 when the latter encounter them in the outward movement of the said slide-bars 12. The lower outer corners of the switch-plates 31 are beveled, as shown at 31^a (Figs. 10 and 12) so that the beveled side edges 31^b of the raised portions 26^a of the pivotal-plates 26 shall readily pass under the plates 31 without undue wear or shock in reciprocating to and from the extended or to and from the closed positions, respectively, of the slide devices.

A suitable spring 26^b is used under each of the elevated portions 26^a of the pivotal-plates 26 (Fig. 8) for quickly and positively returning the latter to normal position after the said raised portions have been depressed. Plates 32 are provided in the bottom edges of the auxiliary-slides 7 near their outer ends and extend laterally across the respective lower faces of the slide-bars 12 so that they almost touch the tenoned portion 30 (Fig. 13) and so as to contact with the plates 29 on said slide-bars 12, and the contacting sets of plates 29 and 32 coact in the drawing of the auxiliary-slides 7 outward from the housing of the table when it is desired to use the table in extended condition.

The slide-bars 12 are each tenoned or tongued at 12^a along their upper faces, the elevated portions 26^a of the pivotal-plates 26 being flush therewith (Fig. 8), and stop-plates 33 are provided on the upper faces of the said auxiliary-slides 7, a suitable distance rearward from the outer ends thereof, and extend laterally over the main upper surface of the said slide-bars 12 toward but not touching the tenoned portions 12^a for the return engagement of the lower portions of the pivotal-plates 26 that firmly contact therewith when the outer slide-bars that

carry the extra leaves are directed or pushed back toward the table-housing. In Fig. 6 I show the said lower portion of the pivotal-plate 26 as being spaced away from the adjacent edge of the stop-plate 33, but in practice said lower portion should at no time be so spaced, as the outer slide-bars 12 never extend beyond the limit of contact of the lower contacting sets of plates 29 and 32. This manner of showing the pivotal-plate 75 away from said stop-plate is done to bring more clearly to view the structure of the said pivotal-plate and its mounting. Each of the said stop-plates 33 is beveled at but one outer corner 33^a for the ready passage 80 thereover of the lower outer edge of the base or lower portion of the pivotal-plate 26 when the latter has almost approached the end of its stroke in the outward movement of the slide-bar 12 on which it is 85 mounted and the coaction of the bottom-plates 29 and 32 about to be effected. The said bottom-plates 29 and 32 now coact in the further movement outward of the slide-bars 12 and serve to couple the auxiliary-slides 7 with said slide-bars 12 for extending the slides 7 from the housing to the limit of their lower hook-ends 34 that engage the lower cross-bars 35 of the housing-frame. 95

When the slidebars 7 and 12 are fully extended the legs or props 20 can then be lowered on their hinges into vertical supporting-position (Fig. 2) by releasing or withdrawing the latch-bolts 24, and then the two 100 subsidiary leaves 14 and 15 are unfolded from the outermost leaves 13 so as to fill the spaces or gaps between said outermost leaves 13 and the edge of the table-top 4. In the outward sliding-movement of the 105 bars 7 and 12 the inclined tongue and groove connections of the said bars 7 cause the said bars and the extra leaves that they carry to gradually rise to a level that brings the upper surface of the outermost leaves 13 110 flush with that of the said table-top 4, and the reverse action takes place when it is desired to close the extension devices and leaves within the housing or receptacle provided beneath the said table-top 4. The 115 tenon or tongue formations 12^a along the upper faces of the slide-bars 12 serve to support the extra leaves 13 and 14 on the same level as the inner extra leaves 15 that rest on the upper faces of the auxiliary-slides 120 7 and there is thus a substantial base for the said extra leaves throughout their extended positions.

It will be seen, in the operation of the extension devices, that the plates 31 merely 125 serve as switches for the pivotal or rocker plates 26, the elevated portions 26^a of the latter passing under them in both directions of travel and thereby causing the pivotal-plates to rock on their bearings so that 130

the base portions thereof ride freely over the stop-plates 33 when moving in either direction of travel. In the backward movement of the slide-bars 12 the pivotal base-plates 26 engage the stops 33 and serve as couplings until the said switches 31 are reached, at which time the said switches cause the pivotal base-plates to be released from the stop-plates, at which time, also, 10 the auxiliary-slides 7 have been duly housed within the table and then the outer slide-bars 12 can immediately follow without obstruction until the inner edges of the piled-up extra leaves contact with the center-bar 19. 15 It will be seen that the drawings show a square-ended table with my extensible features applied thereto, but it will be quite obvious that my said extensible features are just as well adapted for use in connection 20 with an oval or round ended table.

In operating the extension devices, the set at one end of the main-table is first actuated by drawing it outward from beneath the top 4 until the auxiliary-slides 7 reach 25 the end of their ascending stroke and the hooks 34 are in engagement with the cross-bar 35, which movement brings the upper edges of the rear ends of said auxiliary-slides 7 in contact with the lower face of 30 the said top 4 (Fig. 4) owing to the coaction of the inclined tongues 8 in the inclined grooves 9. The piled-up extension-boards 13, 14 and 15 are still supported at this time on the slide-bars 12 and the bottom-plates 35 29 and 32 are in coacting position for the further advance of the said slide-bars 12 and the extension-leaves carried thereby into 30 final full extended position, but the set of extension devices at the other end of the 40 main-table can now be actuated to the full length of both their ascending and straight-ahead, horizontal stroke, whereby the outermost slide-bars 12 are in the position shown in Fig. 2 and the said extension boards or 45 leaves unfolded into the gap or space between the outer leaf 13 and the edge of the table-top 4. The latch-bolt 24 of the last-named set is then withdrawn from its socket so that the legs 20 can be swung

downward into supporting-position for the 50 outer end of the said last-named extension-set. The completion of the outward stroke, in a horizontal plane, can now be accomplished in connection with the first-named set so that the extension leaves or boards 55 can be utilized in closing the gap or space between the board 13 and the edge of the top 4 (Figs. 1, 2 and 4) and the latch-bolt 24 in that set adjusted so that the legs 20 thereof can be dropped into leaf and extension 60 device supporting-position. The closing of the extension devices into the receptacle beneath the table-top 4 is accomplished in a reverse manner, and one or more persons can thus readily handle the device equally well 65 and without parting any of the main-table or rolling any of it over the floor.

I claim:—

In an extension-table, extensible-slides each comprising an outermost carrier-bar 70 having a horizontal T-shape outer groove intermediate its upper and lower edges, an intermediate auxiliary slide-bar having a horizontal T-shape formation provided along its inner face to slidably-engage the 75 said T-shape groove in the outermost carrier-bar and, also, having an inclined T-shape formation provided along its opposite or outer face, an immovable side-bar in a table-frame having an inclined groove 80 adapted to the sliding-engagement of the said inclined T-shape formation on said auxiliary slide-bar, interlocking or abutting plates for coupling said outermost carrier-bar and auxiliary slide-bar, a transverse 85 rocker-arm on said outermost carrier-bar, a stop-plate on the said auxiliary slide-bar and projecting laterally into the path of said rocker-arm whereby the latter shall engage said stop-plate for the return movement of the auxiliary slide-bar, and means on the table-frame for actuating the rocker-arm in both the reciprocal movements of the auxiliary slide-bar.

LUDWIG GLATZ.
